UNITED STATES PATENT OFFICE.

LEWIS FERRY MOODY, OF PHILADELPHIA, PENNSYLVANIA.

HYDRAULIC DRAFT-TUBE.

1,315,232.

Specification of Letters Patent. Patented Sept. 9, 1919.

Application filed January 22, 1919. Serial No. 272,432.

To all whom it may concern:

Be it known that I, LEWIS FERRY MOODY, a citizen of the United States, residing at Philadelphia, in the county of Philadelphia 5 and State of Pennsylvania, have invented certain new and useful Improvements in Hydraulic Draft-Tubes, of which the following is a specification.

1. This invention relates to draft tubes 10 and is particularly intended for use in connection with hydraulic turbines. It will be described as applied to a turbine of the vertical shaft type.

2. In this type of turbine the vertically 15 discharging water must have its direction turned into the horizontal and it is essential for good efficiency at the same time to convert the velocity head of the water leaving the runner into pressure head by the 20 time it reaches the point of final outlet, so that the energy of the discharge will be utilized to lower the back pressure on the turbine runner with substantial gain in power.

25 3. Since only a limited depth is available in practice below the runner of such a turbine, restrictions are imposed upon the dimensions of the draft tube, and in prior constructions the water has been turned into 30 the horizontal by bending the tube into an elbow or by directly impinging the vertical stream against a horizontal surface. Both 35 of these methods are objectionable in that they necessitate sudden changes in direction and velocity of the water and sharp relative shifting between parts of the stream retarding and wasting the energy of the discharge with a resultant increase in back pressure and a loss of power. Particularly 40 serious losses occur in such constructions when the disturbances are aggravated by initial non-uniform flow, such as is the ordinary condition of water leaving the turbine runner, where there are turbulent eddies and 45 cross currents and often a whirling of the stream as a whole tending even to form a central cavity.

50 4. The object of this invention is to provide a draft tube which will gradually and continuously turn the discharge into the horizontal and simultaneously convert its velocity head into effective pressure head without abrupt changes in speed or direction at any point or the formation of waste-

ful disturbances. This is accomplished by progressively spreading the discharge downward and curving it outward into the horizontal plane symmetrically around a central expanding conical core, so that all transverse elements of the stream go through substantially the same gradual change in direction and velocity together. The stream lines are thus maintained substantially parallel at each point as in a straight tube and are simply bent outward symmetrically around 60 the axis without abrupt change in direction at any part of the stream. Eddies and disturbances are smoothed out and any whirling of the stream is usefully expended in 65 expanding it.

70 5. Simultaneously the velocity of the outflow is lowered by a gradual increase in the transverse sectional area of the tube passage and upon the dimensions of this passage depend the exact rate of this increase 75 and the efficiency of the draft tube. The importance of the exact rate of increase in sectional area has been fully demonstrated in the case of straight draft tubes and rules for the most efficient designs under given 80 conditions have been established. Since in the draft tube of this invention, all the stream elements curve simply from their straight path, all parts of any given transverse plane have nearly the same velocity 85 and the longitudinal stream lines are substantially parallel. With this gradual curvature there are thus maintained conditions of flow closely similar to those in a straight tube and by allowing for the curvature and 90 spread of the new passage its successive cross-sections may be calculated the same as they would be for equal distances of flow in a straight tube. It is therefore possible to apply the established rules for the rate 95 of increase in area to the new conditions and definitely determine the contour of the curved tube walls for full efficiency.

6. Furthermore where the practical limitations of the installation make desirable a shorter, sharper bend of the tube, the resulting variations in flow due to this sharper curve occur in such a regular manner in the draft tube of this invention, that accurate allowance can be made for them and efficiency and power maintained.

7. In the accompanying drawings, Figure 1 is a central vertical section of a

draft tube formed according to this invention;

Fig. 2 is a similar diagrammatic view of a straight draft tube;

5 Fig. 3 is a similar diagrammatic view of a tube of this invention illustrating a method of determining its dimensions;

10 Fig. 4 is a horizontal sectional view on line 4-4 of Fig. 5 of a draft tube of this invention showing the discharge passages to the tail-race;

15 Figs. 5 and 6 are vertical sections respectively on lines 5-5 and 6-6 of Fig. 4, and

20 Figs. 7 and 8 are diagrammatic views illustrating the manner of applying the correction to the width of a bent channel and to that of a small section of a flared pipe or draft tube.

25 Figs. 9 and 10 are sections illustrating a spiral conduit that may be employed in connection with my improved draft tube.

30 8. This invention may be advantageously applied to draft tubes molded in a concrete substructure as shown in Fig. 1, where A is the vertical shaft turbine runner, B the sub-structure and C the draft tube showing one embodiment of this invention. The water discharging from the runner A flows downward into the draft tube at 6 in a circular stream of an initial diameter 7-8 around the vertical axis D-D. In the embodiment shown, the first portion 6-9 of the draft tube is formed as a straight section expanding in diameter to 10-11 at 9 with corresponding deceleration of the outflow. Below this straight part the discharge of the stream is turned outward all around the axis D-D along the curves

35 40 12-13-14 between the conical core E and the spaced confining wall F. The stream is thus spread into the horizontal plane so that the water leaves the tube in a radially outward direction with respect to the axis

45 50 55 on all sides, being distributed with substantial uniformity throughout the annular discharge space 20 forming the outlet from the tube. At the same time the cross sectional area of the stream is progressively

60 expanded to continue the deceleration of the outflow so that simultaneously with the change in direction, the velocity head is converted into effective pressure head. In the embodiment shown in Fig. 1, a short

65 65 70 conical draft tube 6 to 9 is used as a transition tube between the runner discharge space and the beginning of the curved tube. The beginning of this curved portion could if desired be placed immediately at the runner discharge and this will in many cases be the preferable arrangement. Where

75 80 85 space permits however, such a straight transition tube is of value, since it gives a preliminary reduction of velocity before the entrance into the curved flaring portion and

the use of the straight portion is not objectionable if space remains below it to design the flared part of the tube with sufficiently gradual curvature.

tween the central and side surfaces, and r is the mean distance of the line n from the axis D—D, *i. e.*, the radial distance from point 41 to the axis D—D. In order to determine the value for n for a most efficient increase in area of the discharge section, it is only necessary to give it such a value that the corresponding cross section will be the same as that for a straight conical draft tube at the same point of flow, *i. e.*, $2\pi rn$ will equal πR^2 , where R is the radius a straight tube would have at an equal distance of flow from the section 9, 10, 11; as at point 43, Fig. 3, where line 9 to 43 is equal in length to S, the length of line 12 to 41. The most efficient value for R thus determined will be substituted in the equation $2\pi rn = \pi R^2$, and the value of n obtained from this equation is laid off one-half on each side of the central line. By stepping off a series of such points along the axis D—D and the curve 12, 13, 14, and similarly obtaining the successive values R' , R'' , etc., n' , n'' , etc., the complete form of the central cone E' and side surfaces F' will be accurately determined as the surfaces of revolution generated by revolving the curves passing through the ends of the normals n , n' , n'' , etc., around the vertical axis D—D.

12. Experimental researches of the ordinary form of conical draft tube have shown that the best efficiency is obtained when the angle of flare is in the neighborhood of 3° to 4° . One of the advantages of the type of draft tube covered by this application is the fact that when a curved central cone is introduced the water is guided more definitely on all sides, and it becomes possible to increase the equivalent angle of flare of a straight draft tube having areas corresponding to the curved flaring tube, to values considerably above 4° without materially reducing the efficiency. It has been found from tests that the equivalent angle should be kept between about 3° and about 15° to insure good results. A considerable range of values is therefore available without seriously reducing the efficiency. The equivalent conical draft tube is not necessarily made with a single angle from top to bottom but this angle may be progressively increased from entrance to discharge without requiring any change in the method of design described. The advantage of using a larger angle of flare than the 4° or thereabout, which must be used with the ordinary type of draft tube, is that the velocity can be reduced within smaller space limits without seriously increasing the losses of energy.

13. The above method of laying out the design of the draft tube may be applied exactly as described, when the space limitations permit the use of large radii of curvature of the channel center-line at all points. When, however, it is necessary to use a considerable

degree of curvature for transition from vertical to horizontal, a correction is called for in the width which should be provided for the channel. In the preceding discussion the velocity of flow at any given transverse section of the draft tube has been spoken of as if this velocity were the same at all points of any such transverse section. This would indeed be very nearly true when the walls of the passage in the direction of the flow have but little curvature. When, however, the curvature is rapid, that is when the radius of curvature is no longer very great in comparison with the transverse width of the passage, the centrifugal force of the water flowing in such a curved channel increases the pressure on the side of the channel away from the center of curvature, and reduces it on the other, and as a result the velocity decreases on the side having increased pressure and increases on the other side. If the preceding method of design is adhered to for channels having rapid curvature, the average velocity over any transverse section will still decrease in the same manner as in the preceding method. Due to the variation of velocity across the lines of flow, however, the velocity at the inner and outer walls of the channel will vary in a different manner. The correction herein proposed to care for this velocity variation consists in increasing the width of the portions of the channel having rapid curvature sufficiently to maintain the desired rate of velocity reduction from section to section in the maximum velocity occurring at each section, rather than applying it to the average velocity at each section. This maximum velocity occurs along the wall nearest to the center of curvature of each section. If this correction is not applied, the high velocities along the outer wall of the flaring draft tube instead of continually decreasing at the desired regular rate will either decrease at an insufficient rate, or may even increase, and will then subsequently decrease with undue rapidity.

14. The corrected widths of channel N N' etc., from point to point will be greater than the widths n , n' , etc., determined by the method given above and the increase will be greater at points of greater curvature so that the resulting enlargement of the tube section correctively decelerates the flow at the outer wall in exact opposition to the acceleration due to the curvature.

15. To explain the matter more clearly, before taking up the magnitude of the correction which is to be applied in a channel of the form above described (that is, one in which the flow is in radial planes having a common axis) let us consider the flow in a simpler form of channel, such as a bend or elbow in a canal or pipe of uniform rectangular cross section. In the usual design of such a canal or pipe bend, the channel is

bounded by two parallel plane surfaces, and by two concentric cylindrical surfaces, the channel being of constant width measured normally to the flow at all points. As a result, the unequal distribution of velocity in any cross section, caused by centrifugal force, forces the water flowing on the side nearest to the center of curvature of the bend to increase to a considerably higher value than the velocity in the straight portions of the pipe or canal leading to the bend or away from the bend. This increased velocity occurs at the very point where high velocity is particularly undesirable, namely, along the wall having the most rapid curvature, and this results in a harmful acceleration and subsequent retardation of the velocity along this wall, and gives rise to eddies and consequent losses of energy. In applying the correction here proposed to the design of such a pipe or channel bend in which the purpose of the bend is merely to change the direction of flow, but to deliver the water into a discharge channel with the same velocity as that existing in the entrance channel, the width normal to the lines of flow at each section of the bent portion of the channel would be increased sufficiently to maintain a constant velocity at all points of the inner wall, that is, the wall nearest to the center of curvature of the bend. This increase in width would be greater at points having more rapid curvature. In addition to this, the center line of the channel would be designed with curvature gradually increasing up to the center of the bend and then gradually decreasing in a manner similar to that already described in connection with the flaring draft tube. In accordance with this method, the channel will be widest at the middle of the bend and will taper in each direction to the width of the uniform straight portions of the channel. My method of determining the amount of correction to be applied to the width is based on the assumption of a uniform variation of velocity transverse to the lines of flow; that is, the velocity in a transverse section is assumed to vary in accordance with the "straight-line" law.

16. Assuming in advance that it is possible to design a bend or elbow in which the losses of head are very small, the sum of the pressure-head plus the velocity-head will be practically constant at all points in the stream. If we design the bend to maintain a constant pressure-head along the inner wall, the velocity-head and consequently the velocity must also be constant at all points of this surface in accordance with the above assumption.

17. From a mathematical investigation of systems of hyperbolic curves, including both rectangular hyperbolas and hyperbolas of the third degree (having the equation

$x^2z=a$ constant) it has been found that in such systems or curves the radius of curvature varies uniformly along a line drawn normal to all of the curves of such a system. If the hyperbolic curves be taken to represent flow lines, and if we integrate the differential change in pressure due to the centrifugal force of any elementary stream filament, it is found that the velocity varies uniformly from point to point along all lines normal to the flow. Whether this uniform variation of velocity transverse to the flow be regarded merely as an assumption, or whether it be regarded as the result of the mathematical investigation described, it will be adopted here for reasons of simplicity.

18. Assuming, then, a uniform variation of velocity across a transverse section of the above pipe bend or elbow, it is also found, from the above integration for the change in pressure due to centrifugal force, that the rate of variation of velocity across the lines of flow is such that if continued outside the channel the velocity would become zero at a distance from the axis of the channel equal to the radius of curvature at the section considered, this zero point of velocity occurring, however, on the opposite side of the channel from the center of curvature. Fig. 7 is given to illustrate this point. On the basis of the above considerations, the resulting correction which should be applied to the width of the channel at any point may be found as follows: If we denote by n the original width which the channel would have had if this width had been kept uniform around the bend, and by N the corrected width of the stream at any section to satisfy the above requirements, then the ratio in which the stream must be widened is given by the following formula:

$$\frac{N}{n} = \frac{\rho + \frac{N}{2}}{\rho}$$

in which ρ is the radius of curvature of the center line of the channel at the section considered.

19. Now, taking up another form of channel, let us suppose the parallel sides T, T' of the above elbow to be changed into an inclined position, as shown by T', T'' in Fig. 8, so that we now have a wedge-shaped channel which may be considered to be a small section of a large circular stream, similar to that of the draft tube of this invention. If we still consider a case in which the velocity of the water after leaving the bend is the same as the velocity of the water before entering the bend, we have a channel similar to that described in the first part of paragraph 10, namely, a flaring tube in which the average velocity is constant at every section transverse to the flow. For the same considerations as already described, the

width of the channel of Fig. 8 should be corrected to maintain a constant velocity along the surface VV instead of maintaining a constant average velocity around the bend. On account of the form of this channel, however, we must take into consideration the distance L from the middle of any section to the point where the plane of the section intersects the axis DD. The above formula will consequently be changed to the following:

$$15 \quad \frac{N}{n} = \frac{\rho + \frac{N}{2}}{\rho + \frac{N^2}{12L}}$$

20. Proceeding one step further, instead of applying the last mentioned correction to the channel described in paragraph 11, we can equally well apply it to a gradually enlarging channel such as that representing the chief subject of this disclosure, and constructed as described in paragraphs 11 and 12. The amount of widening to be applied 25 at any section of a channel so designed is therefore given by the formula last stated above, in which:

30 n = original width of channel at any section as obtained from the method given in paragraphs 11 and 12 (Fig. 3).

35 N = corrected width of channel to allow for curvature.

ρ = radius of curvature of center line of channel at section considered.

40 L = distance from center of channel to intersection of the line of the section with the axis of symmetry. (See Fig. 3.)

21. It is not convenient to solve this formula directly for N since this involves the solution of an equation of the third degree. 45 It may however, be readily solved by first assuming tentative values for N at successive points on the curve 12, 13, 14, for instance where n , n' , n'' , etc., are already de-
50 termined, and then solving for $\frac{N}{n}$ the com-

putation being repeated if the resulting value of N differs appreciably from the tentative value. Successive values of N , N' , N'' , etc., will then be laid off along the corresponding n , n' , n'' , etc., and one-half on each side of the center line. The finally corrected form of channel E, F, Fig. 1, will then be determined as the surfaces of revolution generated by the curves, passing 55 through the ends of lines N , N' , N'' , etc., rotated around the vertical axis D—D.

22. This final correction will maintain a gradual and continuous deceleration of velocity along the outer walls and enable the 60 tube of this invention to be applied under

all practical conditions for turning the flow into the horizontal in a smooth and efficient manner.

23. In Figs. 4, 5 and 6, a particular embodiment of the draft tube of this invention 70 is shown in relation to the other elements of the structure. The outer walls F of the tube C are formed within overhang B of the sub-structure B and around this overhang and the discharge annulus 20 are 75 formed the outlet passages G, G' increasing in cross section toward the final outlets at O on each side of the pier V. This pier in the particular design shown is added for structural reasons to provide additional support for the power house. The curved tube may be combined with a straight transition section in any way dictated by the limitations of specific installations and a spiral or other form of collection tube may be used 80 to receive the water from the outlet 20 and may be designed with further increasing cross section to further convert the velocity into pressure head as shown in Fig. 4. The spiral collecting or regaining tube may also 85 begin within the limits of the flared channel here described, spiral walls 25 being inserted in the space between walls E and F as shown in Figs. 9 and 10. Under all circumstances the exact contour of the flaring 90 passages required to give the desired velocity reduction and change of direction may be accurately and readily predetermined.

24. It is obvious that while the invention has been illustrated in connection with its 100 special application to the discharge of a vertical turbine it may be used in a horizontal turbine, or in other connections such as a pump diffuser, or a pipe or conduit.

105 I claim:

1. A hydraulic conduit comprising guiding passages having central and side surfaces directing the flow in curves symmetrically flaring from a central axis and with cross sectional areas increasing gradually in 110 the direction of flow.

2. A hydraulic conduit comprising guiding passages having central and side surfaces directing the flow in substantially hyperbolic curves symmetrically flaring from a central vertical axis, said passages increasing in 115 cross section in the direction of flow.

3. In a hydraulic conduit, a conical core symmetrically flaring from a central vertical axis and concave away therefrom in a plane containing said axis, in combination with a side wall around the said core and spaced therefrom, the linear width of the space being less, but the area of cross section being greater in accordance as the sections are 120 taken farther from the axis.

4. In a hydraulic conduit, a conical core symmetrically flaring from a central vertical axis and having its sections containing the axis concave away from said axis to 125 130

- turn the stream lines gradually without abrupt change in direction, and side walls co-operating with said core to form passages increasing in cross section in the direction of flow.
5. The combination with a hydraulic turbine of a draft tube therefrom comprising guiding passages adapted to spread and turn the outflow around a central conical core, a straight transition tube interposed between the turbine runner and said passages.
10. 6. The combination with a hydraulic turbine of a draft tube therefrom comprising a central conical core, a straight transition tube interposed between the turbine runner and said core, and side surfaces extending from said straight tube and co-operating with said core to form a passage in continuation of said tube.
15. 7. The combination with a hydraulic turbine of a draft tube therefrom comprising a central conical core, a straight transition tube interposed between the turbine runner and said core, and side surfaces extending from said straight tube and co-operating with said core, said straight tube and the passage between said side surfaces and core increasing in cross section in the direction of flow.
20. 8. In a hydraulic conduit means for changing the direction of flow comprising a central axial conical core having its section containing the axis concave away therefrom and co-operating side walls correspondingly convex toward said axis, said core and walls forming between them a radially flaring passage of increasing sectional area in the direction of flow.
25. 9. In a hydraulic conduit means for changing the direction of flow comprising a central axial conical core having its section containing the axis concave away therefrom and co-operating side walls correspondingly convex toward said axis, said core and walls forming between them a passage gradually increasing in curvature in the direction of flow and then decreasing in curvature from an intermediate maximum.
30. 10. In a hydraulic conduit means for changing the direction of flow comprising a central axial conical core having its section containing the axis concave away therefrom and co-operating side walls correspondingly convex toward said axis, said core and walls forming between them a passage gradually increasing in curvature in the direction of flow and then decreasing in curvature from an intermediate maximum, said maximum being located between the middle and discharge end of said passage.
35. 11. In a hydraulic conduit means for changing the direction of flow comprising a central axial conical core having its section containing the axis concave away therefrom and co-operating side walls correspondingly convex toward said axis, said core and walls forming between them a symmetrical passage radially flaring from the central axis in substantially hyperbolic lines.
40. 12. In a hydraulic conduit means for changing the direction of flow comprising a central axial conical core having its section containing the axis concave away therefrom and co-operating side walls correspondingly convex toward said axis, said core and walls forming between them a symmetrical passage radially flaring from the central axis in substantially hyperbolic lines and having a transverse area increasing in the direction of flow.
45. 13. A hydraulic conduit formed by inner and outer coaxial surfaces of revolution generated by curved generating lines convex toward the axis and spaced to give a regular rate of increase in the cross section of the conduit.
50. 14. A hydraulic conduit formed by inner and outer coaxial surfaces of revolution generated by curved generating lines convex toward the axis and so spaced that the cross sectional area of said passages at any intermediate distance from the entrance end of the conduit is slightly larger than the corresponding section of a straight conical tube of the same entrance and discharge areas.
55. 15. A hydraulic conduit formed by inner and outer coaxial surfaces of revolution generated by curved generating lines convex toward the axis and so spaced that the cross sectional area of said passages at any intermediate distance from the entrance end of the conduit is slightly larger than the corresponding section of a straight conical tube of the same entrance and discharge areas, the amount of excess in area over the straight tube being dependent on the radius of curvature.
60. 16. A hydraulic conduit formed by inner and outer coaxial surfaces of revolution generated by curved generating lines convex toward the axis, and so spaced that the cross-sectional area of said conduit at any distance from the entrance end of the conduit has a value between the limits fixed by the areas, at an equal distance from the entrance end, of straight conical tubes of the same entrance area, the sides of which taper at angles of about 3° and 15° with respect to the axis.
65. 17. A hydraulic conduit having guiding passages formed by coaxial surfaces of revolution the outer and inner surfaces being so curved as to be tangent at one end of the conduit respectively to the walls of a straight pipe and to its axis, and at the other end of the conduit equally spaced from a plane surface normal to the axis.
70. 18. A hydraulic conduit having guiding passages formed by coaxial surfaces of rev-

- olution the outer and inner surfaces being so curved as to be tangent at one end of the conduit respectively to the walls of a straight pipe and to its axis, and at the other end of the conduit equally spaced from a plane surface normal to the axis, the cross sectional area at any point being at least equal to that of a straight flaring tube at an equal distance from the entrance end.
- 10 19. A hydraulic conduit comprising guiding passages having central and side surfaces curving symmetrically from a central vertical axis at all points and formed to maintain a condition of flow at the outer surface equivalent to the corresponding condition in a conical tube.
- 20 20. A hydraulic conduit comprising guiding passages having central and side surfaces curving symmetrically from a central vertical axis at all points and formed to maintain a deceleration of flow at the outer surface equivalent to the corresponding condition in a conical tube.
- 25 21. A hydraulic conduit formed by inner and outer coaxial surfaces of revolution generated by curved generating lines convex toward the axis and spaced to give cross sections across the lines of flow everywhere at least equal to the corresponding cross sections of a conical tube, and the cross sections where the conduit curves being increased beyond such equal relation.
- 30 22. A hydraulic conduit formed by inner and outer coaxial surfaces of revolution generated by curved generating lines convex toward the axis and spaced to give cross sections across the lines of flow based on corresponding cross sections of a conical tube. 35
23. A hydraulic conduit formed by inner and outer coaxial surfaces of revolution generated by curved generating lines convex toward the axis and spaced to give cross sections across the lines of flow based on corresponding cross sections of a conical tube and increased further in correspondence to 40 the degree of curvature of the lines of flow in the conduit. 45
24. A hydraulic conduit formed by inner and outer coaxial surfaces of revolution generated by curved generating lines convex toward the axis and so spaced that the cross sectional area of said passages at any intermediate distance from the entrance end of the conduit is not less than the corresponding section of a straight conical tube of the 50 same entrance and discharge areas. 55
25. A hydraulic conduit comprising guiding passages having central and side surfaces curving symmetrically from a central vertical axis at all points and formed to maintain a smooth deceleration of flow at the outer surface. 60
